Term of patent 14 years

(Cl. D52—7)

Fig. 3

Fig. 1

Fig. 2

FIG. 1 is a front elevational view of a humidistat control embodying my new design;

FIG. 2 is a side elevational view thereof;

FIG. 3 is a top plan view thereof.

The undisclosed side of the humidistat control is substantially the same in appearance as viewed in FIGURE 2, and the rear is plain in appearance.

The essential features of the design reside in the portions shown in full lines.

I claim:

The ornamental design for a humidistat control, as shown and described.
